UNITED STATES PATENT OFFICE

158,331

SHOE

Jacob Sandler, Norfolk, Mass.

Application January 10, 1950, Serial No. 7,110

Term of patent 7 years

(Cl. D7—7)

To all whom it may concern:

Be it known that I, Jacob Sandler, a citizen of the United States of America, residing in Boston, county of Norfolk, and State of Massachusetts, have invented a new, original, and ornamental Design for a Shoe, of which the following is a specification, reference being had to the accompanying drawing, forming part thereof.

The figure on the drawing is a front perspective view of a shoe showing my new design, the opposite side presenting substantially the same appearance as that shown.

I claim:

The ornamental design for a shoe or similar article, substantially as shown and described.

JACOB SANDLER.
